LUBRICATING DEVICE

Hunter B. McElrath, Winston-Salem, N. C., assignor of one-half to J. J. Wright, Jr., Winston-Salem, N. C.

Application January 19, 1937, Serial No. 121,370

1 Claim. (Cl. 81—3.7)

The present invention relates to improvements in lubricating devices, and more particularly refers to devices for prying apart the leaves or laminations of the elliptical or other springs presently employed to suspend the bodies of motor vehicles from the chassis, and additionally to deliver a heavy lubricant thereto such as is essential for the proper and permanent lubrication of these spring parts.

Heretofore devices intended to accomplish this general purpose have proposed to apply a light penetrating oil for the purpose of insuring the delivery of this oil into the tightly associated leaves of the spring but such light oil does not inhere in the space between the leaves but rapidly flows out with the result that the operation of oiling such springs has to be repeated frequently where a light penetrating oil is used.

The invention has for an object to provide a device which will convey to the space between the spring leaves a highly-graphited grease in relatively large quantities to insure not only the complete lubrication of the surfaces of the spring leaves but also to distribute over the entire surfaces of all of the spring leaves a heavy grease that will remain in place for a relatively long time and thus avoid the expensive and tedious operation of frequently repeating the process of greasing the springs.

It is another object of the invention to provide a simple and inexpensive device having great power for the movement of the spring leaves apart and having clear and direct channels for the delivery of the grease.

With the foregoing and other objects in view, the invention will be more fully described herein-after, and will be more particularly pointed out in the claim appended hereto.

In the drawing, wherein like symbols refer to like or corresponding parts throughout the several views:

Figure 1 is a side elevation, with parts broken away, and with the vehicle spring shown in section, of an improved lubricating device constructed in accordance with the present invention.

Figure 2 shows a similar view with the vehicle spring omitted and parts shown in section, and the plunger in a projected position.

Figure 3 is a top plan view of the device, with parts shown in section.

Figure 4 is a vertical cross-section taken on the line 4—4 in Figure 2, and

Figure 5 is an enlarged plan view, with parts broken away and parts shown in section, of the improved plunger.

Referring more particularly to the drawing, 6 designates the frame of the device from one end of which projects the handle 7, and upon the other end of which is the upstanding nose or flange 8, such flange being offset as indicated at

9 in order to assume a proper alignment with the plunger 10. The plunger 10 is horizontally movable back and forth in a rectilinear path being guided and supported by a casing 11 supported at an appropriate elevation above the frame 6 by a plate or web 12.

The plunger 10 is moved back and forth by the action of a lever 13 fulcrumed, as by means of a bolt 14, upon the frame 6 and having an offset portion 15 to permit the upper portion of the lever to lie alongside the frame 6 to which it is pivoted, while the lower or operating portion of the lever 6 lies in the same vertical plane with the handle 7 for the purpose of facilitating the application of physical force to the lever 13, 15 using the handle 7 as an abutment.

The lever 13 extends above the fulcrum point 14 in an upstanding operating arm 16 having a rounded or ball head 17 which projects into a slot 18 of the plunger 10. The plunger 10, forwardly of the slot 18, is formed with a threaded socket 19 and with a plurality of ducts or channels 20 leading from the chamber formed by the socket to the outer tip reduced end of the plunger, which end is chisel or wedge shape as indicated at 21 in order to facilitate the entry of the plunger between the leaves or laminations 22 of the vehicle spring indicated in Figure 1. A hollow threaded nipple 23 is screwed into the socket 19 and the nipple connects with a tube 24 in communication with a source of heavy grease supply, for instance in connection with a grease gun or grease pumping device. If desired the tube 24 may be pivoted to the nipple 23 as indicated at 25, although this is not necessary.

By observing Figure 4 it will be seen that the plate 12 rises from one edge portion of the frame 6 and that the casing 11 is rolled over from the upper edge of this plate 12 in an outward direction away from the plane of the frame 6 whereby the center of the tubular casing 11, shown to be substantially circular in cross-section in the instance shown, is offset to one side of the vertical plane of the frame 6 and has a slot 26 extending longitudinally or axially along the lower or bottom portion of the casing 11. It is preferable to make the plate 12 and the casing 11 in one piece out of suitably heavy sheet metal whereby the lower edge of the plate 12 may be welded or otherwise secured to the frame 6, while the upper portion of the plate 12 is rolled over, outwardly and downwardly in a substantially cylindrical manner with the upper terminal of the piece of sheet metal terminating short of the plate 12 whereby to provide a gap or slot 26 all along the lower part of the casing 11. As shown in Figure 4 the operating arm 16 of the lever 13 is in direct vertical alignment with the axis or central portion of the casing 11 whereby its head 17 may enter up through the slot 26 and lie within the 60

slot 18 of the plunger 10. The operating arm 16 and its head 17 may play freely back and forth in the slot 26 of the casing 11 in accomplishing the movement of the plunger 10 toward and from the nose or flange 8. This nose or flange 8 must be offset so as to bring it in alignment with the axis of the tubular casing 11 or into the direct path of movement of the plunger 10.

In the operation of the device, with the parts substantially in the position shown in Figure 1 the device is applied to a vehicle spring, with the nose or flange 8 extending at one side of the leaves 23 and the plunger 10 presented at the opposite side. The lever 13 is then lifted causing the plunger 10 to advance toward the spring leaves 23 and requiring the chisel or wedge end 21 to enter between adjacent laminations, causing the laminations to move apart. At this time grease from the gun or pump or other source is forced under pressure through the tube 24, socket 19 and ducts or channels 20 directly into the space between such spring leaves. The plunger is withdrawn from between the spring leaves by reverse action of the lever 13; whereupon the elevation of the device is altered in order to present the plunger opposite the next space between spring laminations to be lubricated.

A stop 27 mounted on the guide plate 12 or upon the frame 6 is so placed as to prevent the plunger from disengaging the lever cam 17 when removing the plunger from the spring leaves. In other words this stop 27 engages the operating arm 16 in the completely retired position of the plunger 10 whereby to prevent the operating arm 16 from swinging down further to the right which would eventually result in the head 17 moving completely below the slot 18; in which case the plunger 10 would be free to be backed out of the casing 11. The casing is open at both ends and it is also open along the bottom 16 to permit the free movement of the operating arm 16 and the free movement of the nipple or fitting 23 in the act of reciprocating the plunger.

It will be appreciated from the foregoing that the improved device substantially eliminates the laborious task of getting heavy grease between spring leaves and renders it a simple matter to apply heavy graphited grease into such spaces. The lever 13, so constituted and arranged, exerts a powerful force upon the chisel-pointed channeled plunger 10 requiring the plunger to move between the spring leaves and causing application of grease through this same plunger, under pressure, to unlubricated sections of the spring leaves. The lubricant supply being directly connected to the lubricating device, no time is lost in applying the grease after the spring leaves are pried apart.

It will also be noted that the plunger is given a horizontal motion and is mechanically operated with a minimum effort through the leverage obtained. In this way the device lends itself to rapid work and to the efficient placement of heavy lubricant in contact with all surfaces of the spring leaves.

Another important point is that the device is designed for work in places that are substantially not accessible to similar prior devices. This result is brought about by the curvature of the handle 7 and lever 13 downwardly. In all vehicle construction there is a road clearance line. Nothing is permitted to project below this line. The curvature referred to carries the handle 7

and the operating lever 13 below the road clearance line. Thus they are in an unobstructed space for easy and quick operation. The distance between the nose or flange 8 and the far end of the plate 12 and casing 11 is a comparatively short one, thus presenting a relatively compact operating unit to extend above the road clearance line. Even the frame 6 may project just below this line.

The plunger moves in a direct horizontal path 10 parallel with its point of entry between the spring leaves. This facilitates the movement of the leaves apart and it also reduces the power input as against a plunger that moves in an arcuate path. The plunger guide or casing 11 maintains 15 a true horizontal alignment of the plunger 10 in its movement into and out of the spaces between the spring leaves; thus one direct pull on the powerful lever 13 will send the wedge 21 home between the spring leaves and another reverse pull 20 of the lever removes the wedge. Thus the action is simple and direct and is substantially instantaneous. This insures rapid work.

The plunger 10 may be fitted with a grease fitting at 23 in order that the lubricator may be 25 applied to the spring first, and then the grease line placed on the fitting; after which the operator may open the valve in the grease line to lubricate the spring. The guide 11 will act as an abutment to engage the side of the spring 22 and 30 enable the member 10 to be more easily withdrawn from between the spring leaves. While the spring in Figure 1 is shown as spaced from the guide 11, in actual practice the entire tool shifts over upon initiating withdrawal of the 35 member 10 and the adjacent end of the guide 11 shifts over against the near side of the spring 22. The member 10 may then be very easily withdrawn from between the spring leaves by the 40 operation of the lever 13.

It is obvious that various changes and modifications may be made in the details of construction and design of the above specifically described embodiment of this invention without departing from the spirit thereof, such changes and modifications being restricted only by the scope of the following claim.

What is claimed is:

A lubricating device comprising a straight frame member, an abutment upstanding from 50 one end of said member, an elongated handle integral with the other end of said member and inclined in a direction opposite from said abutment, a longitudinally slotted guide cylinder disposed in parallel relation to said member and 55 having an end confronting said abutment, means secured to said cylinder and said member supporting said cylinder in offset relation to said member, a plunger slidable in said cylinder and having a slot intermediate the ends thereof, a 60 wedge-shaped bit on an end of said plunger having a duct opening therethrough terminating adjacent the end of said plunger, means secured to the plunger extending through the slot of said cylinder connecting said duct to a source of lubricant supply, a lever pivotally secured to said member and extending on the same side of said member as said handle, an obliquely disposed arm integral with said lever, and a disc-shaped head carried by said arm engaging in the slot 70 of said plunger.
